PACKAGING METHOD AND MEANS

Robert J. Hickin, Rittman, Ohio, assignor to The Ohio Boxboard Company, Rittman, Ohio, a corporation of Ohio

Application January 15, 1951, Serial No. 206,099

16 Claims. (Cl. 53—7)

1

In the packaging of various commodities in salable multiples of individual containers such as bottles, cans and the like, in cartons, boxes, cases and crates, it is customary to provide between the rows of containers separator or partition strips, usually in crisscross, interengaged arrangement, providing individual cells for the several containers, to thereby guard against breakage, defacement of labels and other possible damage, and also to enhance the strength, compactness and sales appeal of the packaging.

This practice is particularly advantageous in the formation of the so-called "six-bottle" packages of beverages which have lately been resorted to for the sale of such bottled beverages in easily-transportable multiples.

Ordinarily, in forming a package of a multiple of containers such as bottles or cans, with the cell-forming separator or partition strips, the carton, box, case or crate is set up to relatively finished form, the pre-assembled cellular arrangement of separator or partition strips is inserted in the said carton or the like, and thereafter the containers, either singly or in appropriate multiples, are deposited in the individual cells. This mode of procedure requires a number of separate operations upon, and handling of, the several elements ultimately making up the package, and usually some of these operations are manually performed.

The object of the present invention is to reduce to a minimum the manually performed operations now required in this general type of packaging procedure, thus to attain increased packaging speed and simplify and reduce the cost of the packaging operation.

In accordance with the invention, and taking the "six-bottle" packaging of bottled beverages, such as beer, as an example, the filled and capped bottles coming from the bottling machine will be packaged in appropriate cartons with interposed cell-forming separator or partition strips, and the cartons sealed in salable, transportable condition, wholly automatically; the only manual operations required being those necessary to the maintenance of adequate supplies of separator or partition strips to the mechanisms which feed and assemble them, and of carton blanks to the mechanisms which feed them to the packaging line.

To these ends, the invention comprises a method and means for packaging articles, especially bottles, whereby the same may be gathered in selected, predetermined multiples (say of six bottles) with separator or partition strips in

cell-forming arrangement between them, and the assemblies of bottles and separator or partition strips held between them enclosed, as units, in appropriate cartons formed from blanks which are folded about them and sealed into finished carton form, such operations being performed automatically, all as will be explained hereinafter more fully and finally claimed.

In the accompanying drawings, which disclose somewhat diagrammatically, or schematically, means for automatically carrying out the method of the invention, and in the several views of which like parts are similarly designated,

Figs. 1a, 1b, 1c, when arranged serially end to end depict, in side elevation, one form of apparatus suitable for performing the packaging operations in accordance with the invention,

Fig. 2 is a fragmentary plan view of portions of two of the belt conveyors shown in Figs. 1a and 1b.

Fig. 3 is a sectional elevation taken on line 3—3 of Fig. 1b and showing parts of the mechanism for completing the assembly of separator or partition strips with the selected groups or multiples of bottles.

Fig. 4 is an enlarged fragmentary sectional elevation of parts of the partition strip assembling mechanism shown in Fig. 3.

Figs. 5 and 6 are further enlarged fragmentary detail views illustrating the operation of the shuttle bar flap member of the strip assembling machine,

Fig. 7 is a perspective view of a set of separator or partition strips in position prior to their interengagement in completed assembly,

Fig. 8 is a plan view, upon a greatly reduced scale, of a folding carton blank suitable for use in the practice of the invention, and

Fig. 9 is a view similar to Fig. 8, but showing the end wall members folded over to prepare the blank for feeding to the apparatus of the invention.

Figs. 10a and 10b when taken together represent, schematically, suitable mechanism for progressively feeding, folding, gluing, erecting and glue-sealing the carton blanks; the means for delivering, feeding and assembling the bottles, and for associating them with the cartons being omitted in the interest of simplicity of disclosure.

50 In the embodiment of the apparatus shown, it will be seen (Figs. 1a, 1b) that as the filled and capped bottles leave the bottling machine (not shown) they are picked up in pairs, laterally (Fig. 2) upon a belt 1 travelling continuously

55 in the direction of the arrows a upon a rigid

platform 2 and are maintained in orderly arrangement by side guide rails 3.

Above the bottles is arranged another belt 4 the lower pass of which travels in the same direction and at the same speed as the belt 1 and this latter belt 4 carries a plurality of laterally arranged pairs of clips 5 equally spaced in conformity with the spaces between bottles upon the belt 1. Adjacent to one end of the belt 4, where it passes around its carrying and driving pulley 6 is a feed mechanism for the transverse separator or partition strips 7 (Fig. 7) having a feed table 8 in which reciprocates a pusher plate 9 serving to progressively and successively feed the lowermost strips 7 from the bottom of the stack thereof into the nip of a pair of rapidly rotated feed rolls 10 by which they are projected into successive pairs of clips 5 as the latter reach the registering position shown in Fig. 1a. It will be noted, however, that the feed table 8 is provided with a lifter member 11 actuated by a cam 12 so driven by gearing 13-14 and chain and sprocket mechanism 15 from the shaft of the pulley 6 of the belt 4 as to be properly timed to raise the stack of partition or separator strips 7 out of position for engagement by the feeding pusher plate 9 at the time of register of every third pair of clips 5 into position to receive a strip. Thus, as shown in Fig. 1a, every third pair of clips 5 will lack a partition strip, and when the partition strips carried by the belt 4 travel in the direction of the arrow b above the bottles, and are stripped from the clips by a slanting stripper finger 16, they will drop into the spaces between pairs of bottles directly below them and will thus automatically define multiples of six bottles the two outer pairs of which are to be separated from the respective inner pairs by the pairs of partition strips 7.

As the belt 1 carrying the bottles with deposited partition strips resting between their necks (Fig. 1a) moves along the platform 2, it passes over a raised idler roller 17 which causes the belt to take an upward buckle thus presenting a ridge over which the bottles travel and by which they will be tilted, as shown, to permit the partition strips to drop down between them into contact with the belt.

Having reference to Figs. 1b and 2, it will be seen that the bottles, with the partition strips 7 between them, pass from the belt 1 onto a belt 18 which is given a greater linear speed than that of the first belt 1 thus to gain spacing, and hence time of travel, of the bottles so that they may be appropriately fed, at right angles to the belt 18, in groups or multiples of six, over the bed 19 of partition assembling mechanism c (Figs. 1b, 3 and 4) which is similar in major features of design and function to that disclosed in applicant's copending application for patent for Partition Assembling Machine, filed July 22, 1947, Ser. No. 762,616, now Patent No. 2,594,924, dated April 29, 1952.

This mechanism comprises essentially a feed table 20 and hopper 21 for the longitudinal separator or partition strips 22 (Fig. 7), a feeder plate reciprocated by link and lever mechanism 23 and mating feed rolls 24 (only one of which is shown) mounted on shafts 24' and which serve to successively feed the partition strips in interleaved relation into a feed path defined by a fixed guide plate 25 and a spring-actuated guide sheet 26 by which the strips are guided in a continuous, interleaved sheet (so to speak) into a feed throat 27 (Figs. 3 and 4) where the bottom edge of the

leading strip, and hence the interleaved series of strips, is arrested by stop pins 28 the ends of which are normally held in throat-intercepting position (Fig. 4) by springs 29. Beneath the throat 27, and having their nip in alignment therewith, is a pair of feed rollers 30, 31, one of which, 30, is constantly driven clockwise by belt and pulley mechanism 32, 33 from a motor 34. The other feed roller 31 is an idler and pressure applying roller and is mounted in spring-pressed sliding bearing blocks 35 connected by adjustable links 36 with lever arms 37 on a rock shaft 38 to which oscillation is imparted by a rock lever 39 actuated by means such as a solenoid magnet 40 energized and deenergized in timed relation to the travel of multiples of bottles over the bed 19, as will be explained later. Also, the stop fingers 28 are given similarly timed actuation by the connection of their operating levers 41 with links 42 connected with lever arms 43 on the rock shaft 38. The links 42 carry a transverse shuttle bar 44 (Figs. 4, 5 and 6) operative in timing feed of partition strips from the throat 27, and having a hinged downwardly-extending flap member 45 the purpose of which will be explained hereinafter.

The multitudes of bottles are advanced over the bed 19 by automatically depressible, normally offstanding, pusher plates 46, which may be spring erected as indicated at 47, Fig. 4, carried by laterally spaced conveyor chains 48 the upper passes of which run flush with the top surface of the bed 19 in channels 49. These conveyor chains are carried by spaced pairs of sprockets 50, 51 and are driven by chain and sprocket gearing 52 through a speed-reduction gearing 53 from a motor 54.

As the groups or multiples of bottles are moved along the top of the bed 19 by the pusher plates 46, in relative spaced relation, they will successively reach a position where the spaces between their two series of three bottles, and hence the medial slots of their respective partition strips 7, will lie directly beneath the throat 27. At this time due to actuation of trip mechanism (not shown, but which may be of the type disclosed in the hereinbefore referred to copending application, now Patent No. 2,594,924, or of the type disclosed in the patent of Wilske et al., No. 2,429,007, dated October 14, 1947) carried by the chains 48, the feed mechanism at the throat, including the stop fingers 28, the shuttle bar 44 and the feed rollers 30, 31, will function to feed a longitudinal partition strip 22 from the throat into mating relation with the two transverse partition strips 7 advanced with the bottles. As the shuttle bar 44 clears the path for projection downwardly of the partition strip the hinged flap 45, which due to the nature of its pivot cannot move to the right, Fig. 4, will engage the necks of the bottles comprising the leading set of three bottles of the group and tilt these bottles away from the other set of three bottles to thus clear the way for entrance of the partition strip 22 between the two sets of bottles.

In order that alignment of the longitudinal partition strips 22 may be such when fed that their slots will properly register with the transverse partition strips 7, automatic registering mechanism 55, Fig. 3, is provided, the same being of a nature similar to that disclosed in the copending application hereinbefore referred to.

It will be noted by reference to Figs. 3 and 4 that although the feed mechanism of the partition assembler c is operated continuously, the

spacing of the groups or multiples of bottles is such as to make possible employment of intermittently operating means for the subsequent steps of the packaging operation, as will now be described; but such intermittently operated feed is not essential, as modifications might be made in the mechanism whereby continuous feed could be employed.

Referring now to Figs. 4, 5, 6 and 1c, it will be seen that as the groups or multiples of bottles move from beneath the throat 21, with the assembly of partition strips completed, the necks and caps of the trailing set of three bottles of the group will cause the flap member 45 to swing upwardly upon its pivot and clear their path of movement (Figs. 5 and 6), and further progress will cause the bottles to be moved onto a reciprocable platform 56 between the edge of which and the adjacent end of the bed 19 of the mechanism c the pusher plates 46 will descend (Fig. 3).

Vertically aligned with the platform 56, and carried by sprockets 57, 58 on shafts 59, 60, either one of which may be driven by an intermittent motion imparting means (not shown) is a pair of chains 61, provided with a spaced series of bottle grasping and suspending members each including a fixed transverse plate 62 attached to the chains 61 and hinged carrying at its edges similar plates 63 (Fig. 3). Each of the plates 62, 63 is provided with a fixed jaw 64 and a pivoted jaw 65, the latter being spring pressed toward the former, as shown, for grasping engagement with the necks of the three pairs of bottles of a group. Each of the pivoted jaws 65 is furnished with a trip extension 66 for a purpose later appearing. The outer edges of the hinged plates 63 have hinged to them pressure plates 67 hereinafter referred to.

It will be understood that the intermittent progress of the chains 61 will be so timed that a set of the plates 62, 63 with their grasping jaws 64, 65 will be momentarily stationed above the platform 56 in alignment with the necks of the bottles moved onto the platform. Hence, as the bottles are shifted to the platform their necks will slide in between the jaws, the pivoted jaws 65 yielding sufficiently to accommodate them but firmly grasping them.

Immediately after the bottles are thus positioned, the cam mechanism 68 which is preferably timed in its operation to the travel of the chains 48 by chain and sprocket gearing 69, will lower the platform 56 thus leaving the bottles suspended in the grasping jaws 64, 65, and the chains 61 will be advanced through one step of their intermittent movement to bring another set of plates 62, 63 with their grasping jaws 64, 65 into register over the platform 56, the latter meanwhile having again been raised to its position in horizontal alignment with the bed 19 of the partition assembling mechanism.

As the several sets of plates 62, 63 are thus loaded with bottles suspended from their grasping jaws 64, 65, it will be apparent that, due to the hinged connection between the plates, the outer rows or sets of these bottles will tend to pivot inwardly toward the center row of bottles thus frictionally gripping the transverse partition strips and serving to maintain the partition strip assembly in proper assembled relation with the group or multiple of bottles.

In vertical alignment with and below the groups of bottles conveyed by the chain mechanism 61, is a belt or chain conveyor having a

feeding path portion 70 and a discharge path portion 71. This conveyor is flanked by plows 72 and by sealing plates or wipers 72a of conventional form (Fig. 10b). Flat, partially folded, carton blanks are fed transversely of and upon the feeding portion 70 of the conveyor in appropriately spaced relation conforming to the spacing of the groups of bottles carried by the plates 62, 63. This spacing is determined by lugs or the like on the conveyor. The carton blanks may preferably be of the form shown in Figs. 8 and 9, in which the side wall members 73, Fig. 8, and end wall members 74, 75 are joined to the bottom member 76 by gusset-like members 77 which, with the blanks partially folded, as shown in Fig. 9, and thus fed to the conveyor, will, when the side wall members are folded upwardly, cause the end wall members to spread outwardly with their edges overlapping to provide a glue joint all as will now be more particularly described. This form of carton is disclosed in and covered by the application of Joseph A. McElwee for patent for Handled Carton, filed April 11, 1951, Serial No. 220,417.

Having reference to the schematic showing of Figs. 10a and 10b, read together, it will be seen that the carton blanks are successively fed from a hopper 86 by a conventional, oscillating suction feeder 87 to a pair of conveyor chains 88 provided with carton blank engaging lugs 89 and flanked by guides 90. As the blanks move forward with the conveyor chains 88 under the influence of the lugs 89 they are engaged by conventional plows 91 (only partially shown) which serve to fold the end wall members 74, 74 and 75, 75 with their aligned gusset-like members 77 flat against the side wall members 73 and bottom member 76. As the thus folded blanks progress with the chains 88 they will pass beneath an adhesive or glue applying mechanism including a glue font 92, glue feed rollers 93 and glue applying rollers 94 so laterally spaced and having such segmental carton blank contacting surfaces 95 as to apply the adhesive only to the adjacent edges of the end wall members 74 and 75 flanking one of the side wall members 73 of the blank, as indicated by the stippling at 96. After the adhesive has thus been applied the folded blanks are discharged by the chains 88 upon a dead plate 97.

Travelling transversely of this dead plate 97 is the conveyor 70, and paralleling it is a pair of aligning feeder conveyors 98 all substantially at right angles to the chains 88. It will be noted that the conveyors 98 are provided with feed lugs 99 which engage the trailing edges of the folded carton blanks and properly position the blanks transversely of and at right angles to the conveyor 70 and that this conveyor 70 is provided with lugs 100 for carrying the blanks along to the erecting plows 72.

As the blanks approach the plows 72 their folded end wall members 74 and 75 with the intermediate gusset-like members 77 will rise, or may be erected, to position substantially normal to the side wall members 73, as shown at the left of Fig. 10b, thus presenting the blanks for more ready assembly or erection about the groups of bottles suspended above them.

When the thus erected cartons, with the end wall members 74, 75 overlapping their complements to which adhesive has been applied, emerge from the plows 72 they will be acted upon by the sealing plates or wipers 72a. These sealing plates or wipers are carried by links 101 piv-

oted to levers 102 mounted in bearings 103 rigidly, attached to a travelling chain 104 which parallels the path of travel of the cartons, and also pivoted to the levers 102 are arms 105 carrying rollers 106 or the like contact means for engagement with a cam track member 107. The links 101, levers 102 and arms 105 will preferably be retracted to inoperative position (out of contact with the cartons) by spring or other automatic means, not shown.

Thus, when the cam follower arms 105 engage the cam track 107 the plates 72a will be moved into contact with the overlapping glued end wall members 74, 75 of the cartons and will hold them pressed against the pressure plates 67 until such time as the glue has been given an opportunity to properly set, whereafter the end of the cam track 107 will be reached and the plates 72a will be released with the erection of the cartons completed.

Obviously, the conveyor chains 88, 98, 70 and 104 will be synchronously driven, and driven in synchronism also with the feed of groups of bottles by the chains 61, in order that the successively fed and erected carton blanks may be associated properly with the successively fed groups of bottles.

Thus, as the carton blanks travel with the conveyor 70, 71 their side wall members 73 will be engaged by the plows 72 and folded upwardly to embrace the broad sides of the groups of bottles above them, the end wall members 74, 75 meanwhile automatically spreading outwardly to embrace the narrow sides of the said groups. It will be apparent, as indicated in Figs. 1c, 10a—10b, that a progressive setting up of the cartons to embrace the groups of bottles takes place as the blanks travel upon the feeding portion 70 of the conveyor, and that when they reach its discharge portion 71 they will have been completely assembled about the groups of bottles.

As the thus-far packaged groups of bottles leave the portion 71 of the conveyor, they travel with the chains 61 onto a reciprocable platform 78 similar in major respects to the platform 56, and similarly reciprocated, and as this transfer is effected the trip extensions 66 of the several pivoted grasping jaws 65 will strike against trip lugs 79 on the normally spring-projected cores of solenoid magnets 80, thus causing the jaws 65 to move free of the bottle necks. When this occurs the platform 78 is immediately lowered to a position aligned horizontally with the transfer conveyor means 81 which serves to move the package unit onto a conveyor 82 by which it is transferred to mechanism for closing and interengaging the various end flap members 83, 84 and 85 of the carton.

Obviously, when the platform 78 descends to a point where the grasping jaws 64, 65 are free of the bottle necks, the solenoid magnets 80 will be automatically energized to retract the trip lugs 79 so that the jaws 65 may return, under the influence of their springs, to normal bottle-grasping position, and as the plates 62, 63 make their next progressive movement the magnets will be deenergized so that the trip lugs may again be projected by their springs, as will be apparent from the showing of suitable switch means and electrical circuits (Fig. 1c).

Various changes and modifications are considered to be within the spirit and principle of the invention and the scope of the following claims.

What I claim is:

1. The method of packaging two-ended articles in containers, with separator members interposed between the articles, which comprises the steps of supporting said articles upon one of their ends and while they are thus supported allocating the articles in groups of predetermined multiples, arranging between the articles of such groups while still thus supported separator members serving to prevent contact of the individual articles of the groups with one another, and thereafter supporting the articles by their opposite ends with the separator members between them and enclosing the individual groups of articles and their associated separator members while thus last supported in individual containers presented to them toward their first-mentioned ends.

2. The method of packaging two-ended articles in containers, with separator members interposed between the articles, which comprises the steps of supporting the articles upon one of their ends and while they are thus supported allocating the articles in groups of predetermined multiples, arranging separator members between the articles of the groups while such articles are still thus supported to prevent the individual articles of a group from contacting one another, thereafter supporting the articles of the groups by their other ends and maintaining the assembly of said separator members with such articles by frictional contact therewith of the articles, and while the assembly is thus maintained and supported enclosing the individual groups of articles and their associated assemblies of separator members in individual containers presented to them toward their first-mentioned ends.

3. The method of packaging two-ended articles in containers, with separator strip means interposed between the articles, which comprises the steps of supporting the articles upon one of their ends and while they are thus supported allocating the articles in groups of predetermined multiples by arranging between predetermined articles of a plurality thereof separator strip means extending in a predetermined direction with respect to the articles, thereafter and while the articles are still thus supported arranging transversely of the already positioned separator strip means other separator strip means in interengagement therewith, and thereafter supporting said articles in groups by their opposite ends with the assemblies of separator strips intact in the groups and enclosing the individual groups of articles and their associated strip means in individual containers presented to them toward their first-mentioned ends.

4. The method of packaging two-ended articles in containers, with separator strip means interposed between the articles, which comprises the steps of supporting said articles upon one of their ends and while they are thus supported allocating the articles in groups of predetermined multiples by arranging between predetermined articles of a plurality thereof separator strip means extending in a predetermined direction with respect to the articles, while the articles are still thus supported arranging transversely of the already positioned separator strip means other separator strip means in interengagement therewith to provide a cellular assembly of said strip means and articles, suspending said articles by their opposite ends and maintaining such cellular group assembly by frictional engagement be-

tween the articles and strip means, and while the articles are still thus suspended and the assembly is thus maintained enclosing the individual groups of articles and their associated strip means in individual containers presented to them toward their first-mentioned ends.

5. In apparatus for packaging two-ended articles in containers, with separator members interposed between the articles, means for supporting said articles upon one of their ends, means for allocating the articles in groups of predetermined multiples while thus supported, means for arranging separator members between the articles of the groups while thus supported so that the individual articles thereof will not contact one another, means for supporting said articles by their opposite ends, and means operable while the articles are thus last supported for enclosing the individual groups of articles with their assemblies of separator members in containers presented to them toward their first-mentioned ends.

6. In apparatus for packaging two-ended articles in containers, with separator members interposed between the articles, means for supporting said articles upon one of their ends, means for allocating the articles in groups of predetermined multiples while thus supported, means for arranging separator members in interengagement transversely and longitudinally of and between the articles of the groups while thus supported so that the individual articles thereof will not contact one another, means for suspending said articles in groups by their opposite ends, and means for thereafter enclosing the groups of articles with their assemblies of separator members in containers, said means for suspending the articles including means for insuring frictional engagement between the articles of individual groups and the interposed separator members of such groups so that the groups of articles and their separator members may be suspended as composite units for inclosure in the containers.

7. In apparatus for producing six-bottle packages of bottled goods comprising three rows of two bottles each, means for conveying in elongated series bottles arranged in ranks of pairs, means for depositing transversely between the bottles of three consecutive pairs transverse separator strip means serving to divide the series of conveyed bottles into groups of six, means for depositing transversely of the already deposited transverse separator strip means longitudinal separator strip means for interengagement with the transverse separator strip means to provide a cellular strip assembly associated with the bottles of each group and functioning to prevent contact between the individual bottles of the group, means for holding the bottles of each group suspended with the cellular strip assembly in functional association therewith, and means for enclosing the several groups and their strip assemblies in cartons while thus suspended.

8. In apparatus for producing six-bottle packages of bottled goods comprising three rows of two bottles each, means for conveying in elongated series bottles arranged in ranks of pairs, a conveyor travelling at the same linear speed as the bottles and arranged above the tops of the bottles and provided with clip means in spaced arrangement longitudinally of said conveyor substantially equal to the spacing of the pairs of bottles, means for feeding to all but every third clip means transverse separator strip means, means operable to separate said strip means from said

clip means as the said strips travel above said bottles to thereby deposit strip means transversely between the bottles of every three consecutive pairs thereof to divide the series of bottles into a plurality of groups of six, means for depositing transversely of the already deposited transverse strip means longitudinal separator strip means for interengagement with the transverse strip means to provide a cellular strip assembly associated with each of the groups of bottles and functioning to prevent contact between the individual bottles of the group, means for holding the bottles of each group suspended with the cellular strip assembly in functional association therewith, and means for enclosing the several groups and their associated strip assemblies in cartons while thus suspended.

9. In apparatus for producing six-bottle packages of bottled goods comprising three rows of two bottles each, means for conveying in elongated series bottles arranged in ranks of pairs, a conveyor travelling at the same linear speed as the bottles and arranged above the tops of the bottles and provided with clip means in spaced arrangement longitudinally of said conveyor substantially equal to the spacing of the pairs of bottles, means for feeding to all but every third clip means transverse separator strip means, means operable to separate said strip means from said clip means as the said strips travel above said bottles to thereby deposit strip means transversely between the necks of the bottles of every three consecutive pairs thereof to divide the series of bottles into a plurality of groups of six, means for jogging the pairs of bottles to permit the strip means to drop between them into contact with their sides, means for depositing transversely of the already deposited transverse strip means longitudinal separator strip means for interengagement with the transverse strip means to provide cellular strip assemblies with the several groups of bottles and serving to prevent contact between individual bottles of a group, means for holding the bottles of each group suspended with the cellular strip assembly in functional association therewith, and means for enclosing the several groups and their associated cellular strip assemblies in cartons while thus suspended.

10. In apparatus for producing six-bottle packages of bottled goods comprising three rows of two bottles each, means for conveying in elongated series bottles arranged in ranks of pairs, means for depositing transversely between the bottles of three consecutive pairs transverse separator strip means serving to divide the series of conveyed bottles into groups of six, means for depositing transversely of the already deposited transverse separator strip means longitudinal separator strip means for engagement with the transverse separator strip means to provide a cellular strip assembly associated with the bottles of each group and functioning to prevent contact between individual bottles of the group, means including a travelling conveyor provided with bottle-neck grasping means for holding the bottles of each group suspended with the cellular strip assembly in functional association therewith, and means including carton blank conveying and folding means disposed beneath the suspended groups of bottles and travelling synchronously therewith for enclosing the several groups and their strip assemblies in cartons while thus suspended.

11. In apparatus for producing six-bottle pack-

ages of bottled goods comprising three rows of two bottles each, means for conveying in elongated series bottles arranged in ranks of pairs, means for depositing transversely between the bottles of three consecutive pairs transverse separator strip means serving to divide the series of conveyed bottles into groups of six, means for depositing transversely of the already deposited transverse separator strip means longitudinal separator strip means for engagement with the transverse separator strip means to provide a cellular strip assembly associated with the bottles of each group and functioning to prevent contact between individual bottles of the group, means including a travelling conveyor provided with bottleneck grasping means for holding the bottles of each group suspended with the cellular strip assembly in functional association therewith, means including carton blank conveying and folding means disposed beneath the suspended groups of bottles and travelling synchronously therewith for enclosing the several groups and their strip assemblies in cartons while thus suspended, and means for releasing said grasping means from the bottle necks after such enclosing operation.

12. The method of packaging bottles in containers, with separator means interposed between the bottles, which comprises the steps of allocating the bottles in groups of predetermined multiples, arranging between selected bottles of said groups separator means of strip form extending in a predetermined direction with relation to the said selected bottles, and relatively separating said selected bottles by vertically tilting the same to thus permit said separator means to assume a predetermined appropriate position between said selected bottles.

13. The method of packaging bottles in containers, with separator means interposed between the bottles, which comprises the steps of allocating the bottles in groups of predetermined multiples, arranging between selected bottles of said groups separator means of strip form extending in a predetermined direction with relation to the selected bottles, relatively separating said selected bottles by vertically tilting the same to thus permit said separator means to assume a predetermined appropriate position between said selected bottles, depositing between the bottles of the group separator means of strip form complementary to the separator means already positioned and in arrangement transversely thereof, and relatively separating the bottles by vertically tilting the same in a direction substantially normal to the previous tilting to permit said last deposited separator means to interengage with those already positioned to thereby provide a separator structure of cell form for said bottles.

14. In apparatus for packaging articles in containers, with separator means interposed between the articles, means for allocating the articles in groups of predetermined multiples, means for

arranging between selected articles of the groups separator means of strip form extending in a predetermined direction with relation to the selected articles, means for causing separation of said selected articles to permit said separator means to assume a predetermined appropriate position between said selected articles, means for depositing between the articles of the group separator means of strip form complementary to the separator means already positioned and in arrangement transversely thereof, and means for causing relative separation of the articles to permit said last deposited separator means to interengage with those already positioned to thereby provide a separator cell structure for said articles.

15. In apparatus for packaging bottles in containers, with separator means interposed between the bottles, means for allocating the bottles in groups of predetermined multiples, means for arranging between selected bottles of the groups separator means of strip form extending in a predetermined direction with relation to the selected bottles, and means for causing relative separation of said selected bottles by vertically tilting the same to thus permit said separator means to assume a predetermined appropriate position between said selected bottles.

16. In apparatus for packaging bottles in containers, with separator means interposed between the bottles, means for allocating the bottles in groups of predetermined multiples, means for arranging between selected bottles of the groups separator means of strip form extending in a direction predetermined with respect to said selected bottles, means for causing relative separation of said selected bottles by vertically tilting the same to thus permit said separator means to assume a predetermined appropriate position between said selected bottles, means for depositing between the bottles of the group separator means of strip form complementary to the separator means already deposited and positioned and in an arrangement transversely thereof, and means for causing relative separation of the bottles by vertically tilting the same in a direction substantially normal to the previous tilting to permit said last deposited separator means to interengage with those already positioned to thereby provide a separator structure of cell form for said bottles.
